DESIGN FOR A POCKET TOOL

William Kenneth Yates, Jr., Wilmette, Ill.

Application June 2, 1939, Serial No. 85,306

Term of patent 14 years

To all whom it may concern:

Be it known that I, William Kenneth Yates, Jr., a citizen of the United States and a resident of the city of Wilmette, in the county of Cook and State of Illinois, whose post-office address is 1131 Ashland Avenue, Wilmette, Illinois, have invented a new, original, and ornamental Design for a Pocket Tool, of which the following is a specification, reference being had to the accompanying drawing, forming part thereof.

The figure is a perspective view of a pocket tool, showing my new design.

I claim:

The ornamental design for a pocket tool, as shown.

WILLIAM KENNETH YATES, JR.
